UNITED STATES PATENT OFFICE.

ABRAM M. SWEYD, OF NEW YORK, N. Y., ASSIGNOR TO THE AUTOYRE CO., OF OAKVILLE, CONNECTICUT, A CORPORATION.

DESIGN FOR A LABEL.

51,426.

Specification for Design.

Patented Oct. 23, 1917.

Application filed July 26, 1917. Serial No. 182,984. Term of patent 14 years.

To all whom it may concern:

Be it known that I, ABRAM M. SWEYD, a citizen of the United States, residing at New York, in the county of New York and State of New York, have invented a new, original, and ornamental Design for a Label, of which the following is a specification, reference being had to the accompanying drawing, forming part thereof.

The figure is a face view of a label embodying my design.

I claim:

The ornamental design for a label, as shown.

ABRAM M. SWEYD.

Witnesses:

CHARLES D. BACON,
S. KOPE.
